CEMENTING MACHINE

Stephen Mirandette, Haverhill, Mass., assignor
to United Shoe Machinery Corporation, Paterson, N. J., a corporation of New Jersey

Application October 11, 1933, Serial No. 693,161

8 Claims. (Cl. 12—80)

This invention relates to gages for cementing machines and is herein illustrated as embodied in a machine for applying cement to the marginal portion of a shoe sole.

In the manufacture of shoes, the soles of which are attached by means of cement, it is customary to apply a marginal stripe of cement to the attaching surface of a sole. This marginal stripe extends from a point adjacent to the heel breast line around the toe end of the sole to a corresponding point upon the opposite side. Since the heel end of the sole is commonly secured by fastenings such as nails, it is not customary to apply cement to this portion of the sole and, furthermore, the attaching of any portion of the heel seat of the sole by cement is a distinct hindrance to the operation of heel seat fitting and requires the workman to tear the sole from the upper back to the heel breast line. This may readily damage the shoe. Since it is necessary for the operator of the cement-applying machine to position the sole in the machine by eye, it is likely that the operator will either start the stripe of cement forward of the heel breast line, thereby causing the sole to be imperfectly attached, or else, in an effort to avoid this difficulty, will apply cement to the rear of the heel breast line where it is not wanted and where it is wasted. Accordingly, an object of this invention is to provide an improved sole-locating device or gage by means of which the starting position may be accurately determined and in accordance with the size of the sole. In the illustrated machine, and in accordance with features of the invention, a stop gage movable into operative position to receive contact of an end of the work acts as an abutment to determine the starting position of the work, and operator-controlled means are provided for moving the gage from inoperative to operative position. When the feeding movement of the work is started, the gage is dropped to an inoperative position below the work. As illustrated also, the operating treadle of a machine, having a presser or feed roll mounted upon a movable bracket, is interconnected with the movable support for the gage, the arrangement being such that the gage is moved to inoperative position as the feed roll is moved to operative position to coact with the cement-applying roll which assists in feeding the work.

In the drawings,

Fig. 1 is a side elevation of a cementing machine embodying the invention, and

Fig. 2 is an angular view on an enlarged scale of the gage supporting and adjusting mechanism

showing its relation to the work-engaging rolls of the cementing machine.

For the sake of illustration the machine is herein shown as embodied in the sole cementing machine of Letters Patent of the United States No. 1,928,693, granted October 3, 1933, upon the application of A. S. Johnson. The invention is not limited, however, to this particular cement-applying machine, for the gage may be applied to other machines which operate progressively upon the work. A piece of work such as a sole S is presented to the machine with its edge against the driven edge gage roll 10 where it is grasped between a presser roll 12 and a cement-applying roll 14. The rolls 12 and 14 are driven continuously during the use of the machine in opposite directions, thereby to cause the sole to be moved away from the operator, or to the left in Fig. 2. It is desired that the application of cement should commence approximately at the heel breast line 16 (Fig. 2) and, to aid the operator in so positioning the work, there is provided a stop gage comprising an upright arm 18, and a flattened gage portion 20. The gage 20, normally positioned below the work, may be raised to the position illustrated in Figs. 1 and 2 to receive contact of the heel end of the work and act as a stop against which the heel end of the sole is positioned.

This stop gage 20 is adjustably mounted upon a lever 22 and is in advance of the feeding means. In operative or raised position the upper end of the gage is at a level above the top of the presser roll 12. The lever 22 is pivoted upon a stud 24 carried by a bracket 26 which is secured by a screw 28 to an enlargement upon the column 30 which supports the machine. Inasmuch as the distance between the heel breast line and the heel end of the sole will vary in soles of different sizes, the stop gage 20 is adjustably connected to the lever 22. To this end the lower end of the arm 18 is bent at right angles and is recessed at 32 to give it an angular cross-section. The lever 22 has a projecting table portion 34 upon which this grooved end rests and the lever is provided with an overhanging lip 36 overlying the upright portion of the end of the arm. Index marks 38 on the upper face of the end of the arm coact with the forward edge of the lip portion 36 to indicate the position of the stop gage 20 in accordance with the size of the sole, as designated by numbers adjacent to the index marks 38. To assist the operator in moving the gage from one position to another, there is provided a hand lever 40 pivoted upon the table portion 34.

34 and having a segmental toothed end 42 meshing with teeth 44 cut upon the edge of the lower end of the gage arm. This lever is provided with a spring-pressed plunger 46 coacting with one of a series of dents 48 in the upper face of the table portion 34 so that the hand lever 40 may be moved from one size position to another with a minimum of attention.

In this particular cementing machine, the 10 presser roll 12 is carried upon a shaft 50 journaled in a bracket 52 pivoted at 54 in the frame 56 of the machine. The cement-applying roll 14 is mounted upon a shaft 58 also journaled in the frame of the machine and the two shafts are 15 interconnected by gears 60 which receive power from a driving pulley 62 to drive the rolls in opposite directions. Cement is supplied from a receptacle 64 to the upper face of the cement-applying roll which is surrounded by a casing 66 containing controlling devices or scrapers one of which may be adjusted by means of a knurled screw 68. Adjustably secured by a thumb screw 70 to the outer end of the bracket 52 is a casing 12 containing driving mechanism between the 20 rotatable edge gage 10 and the shaft 50 and so arranged that the edge gage may be adjusted and positioned along the shaft without interrupting the driving connection. The bracket 52 has a depending arm 74 to which there is pivotally secured a rod 76 passing through a bushing 78 in the frame and having thereon a collar 80. A spring 82 surrounding this rod between the bushing and the arm 74 urges the presser roll 12 toward the cement-applying roll 14, contact between the two being prevented by a stop screw 84. This screw 84 is adjusted when setting up the machine at the factory and determines the highest position which the feed roll 12 can assume. Another stop screw 86 coacts with the 25 depending arm 74 of the bracket in order to allow the operator to adjust the spacing between the work-gripping rolls of the cementing machine in accordance with the thickness of the work. The machine is provided with a treadle 30 pivoted at the base of the column 30 and urged upwardly by a tension spring 92. In Fig. 1, the treadle 90 is shown in the depressed position which it assumes when an operator steps on it in order to present a piece of work to the machine. This treadle is connected by a treadle rod 94 to a bell crank 96 which is pivoted upon a bracket 98 secured to the enlarged portion of the column 30. A stop screw 100 carried on the treadle rod limits upward movement of the rod, 35 under the impulse of the spring 92, when released by the operator. The treadle rod has an extension 102 which is secured to the bent right-hand end 104 (Fig. 2) of the stop-gage-supporting lever 22. The upper arm of the bell crank 98 is positioned to engage the collar 88 on the rod 76 connected to the pivoted bracket 74 which carries the presser roll 12, so that depression of the treadle is effective to lower the presser roll to an inoperative position as shown in Fig. 1.

40 In the operation of the machine, assuming that the stop gage 20 has been adjusted by means of the hand lever 40 and that the edge gage 10 has been adjusted by the thumb screw 10, then the sole 8 is positioned with its heel end in engagement with the stop gage 20 and against the edge gage 10, and the treadle, which has been depressed to the position shown in Fig. 1 to permit insertion of a piece of work, is released thereby allowing the stop gage to drop and the sole to 45 be gripped between the coacting rolls 12 and 14.

Movements of the gage 20 and the feed roll 12 are simultaneous and in opposite directions. Consequently, the stop gage 20 is removed from the path of feeding movement of the work before the rolls 12 and 14 grip the work to cause it to move forward. Cement will then be applied progressively around the margin of the sole and the sole removed when the stripe has reached a point on the other side opposite the starting point. This point can be readily determined by 10 inspection and a stop gage is not needed for the purpose. The treadle is then again depressed to separate the coacting rolls and the sole removed and another one presented.

Having thus described my invention, what I 15 claim as new and desire to secure by Letters Patent of the United States is:

1. In a cementing machine for operating progressively upon a piece of sheet material in a predetermined plane, feeding means, a gage movable from an inoperative into an operative position where it will receive contact of an edge of the sheet material presented thereto and act as an abutment to determine the starting position of the work, operator controlled means for moving 20 said gage from inoperative to operative position, and means for removing said gage from said position before the work is fed forward.

2. In a cementing machine for operating progressively upon a piece of work, a driven feed 30 roll, a stop gage movable into operative position where a piece of work presented to the feed roll will contact with the gage, and means for simultaneously rendering said feed roll effective and for withdrawing the gage from operative position.

3. In a cementing machine for operating progressively upon a piece of work, coacting feed rolls, a movable support for one of said feed rolls, a movably mounted stop gage positioned 40 in advance of said feed rolls to be engaged by the work as the latter is presented to said rolls, and means for withdrawing the gage and feeding the work.

4. In a sole-cementing machine, a cement-applying roll, a coacting presser roll, a movable bracket for said presser roll, a stop gage movably mounted adjacent to said rolls and adapted to be operatively positioned to where a piece of work presented to the machine will contact with 50 said gage to locate the work, and means for moving said gage to inoperative position and moving the bracket to cause the rolls to grip the work.

5. In a sole-cementing machine, a cement-applying roll, a coacting work-pressing feed roll, a pivoted bracket for said feed roll, resilient means urging said bracket in one direction to cause the rolls to grip a sole, a stop gage adapted to be positioned in advance of said rolls where 55 it will receive contact of the end of the work when presented between the rolls, a swinging support for said gage, operator-controlled mechanism for swinging said gage support to move the gage into operative position, resilient means urging said mechanism to carry the gage out of operative position, and a connection between said mechanism and the feed roll support whereby actuation of said operator-controlled mechanism in one direction is effective to withdraw the feed 60 roll and to project the gage into operative position.

6. In a cementing machine for operating progressively upon a piece of work, an operating member, a stop gage positioned to limit move- 65

ment of presentation of the work to the operating member as it is brought into contact therewith, means for adjustably supporting said gage in positions at different distances from the operating member in which positions the gage will receive contact of an end of the work presented to the operating member, and means for removing said gage from said positions to an inoperative position out of the way of the work to permit the commencement of progressive operation upon the work.

7. In a cementing machine for operating progressively upon a piece of work, coacting work-gripping feeding members one of which is mounted for movement into and out of coacting relation to the other, a movable support, a gage adjustably mounted on said support, means for determining the position of the gage on the support, and means for moving said support and the

movably-mounted feeding member to carry the gage out of operative position adjacent to the work as the feeding member is brought into operative gripping relation to the work.

8. In a cementing machine for operating progressively upon a piece of work, a lever mounted on said machine, a gage the operative portion of which is adapted to be positioned in advance of the work thereby to contact with and determine the position of the work as it is presented to the machine, said gage being slidably mounted on said lever, a pivoted handle mounted on the lever and interconnected with said slidably gage thereby to move the gage to adjust its relation to the machine in accordance with the size of the work, and means for moving said lever to carry the gage into and out of operative position.

STEPHEN MIRANDETTE.
